7 Claims

ABSTRACT OF THE DISCLOSURE

A fabric softening and brightening composition consisting essentially of (a) a quaternary ammonium salt fabric softener and (b) an oxacyanine optical brightener containing at least one methoxy substituent on the benzene rings. A viscosity-adjusting additive may also be present. An illustrative example of said composition is a mixture of di-(hydrogenated tallow)-dimethyl ammonium chloride and 3,3'-dimethyl-5,5'-dimethoxy-oxacyanine-p-toluene sulfonate.

Detailed disclosure

This invention relates to novel fabric softening and brightening compositions which are useful especially for the simultaneous brightening and softening of the "handle" of textile fabrics and the like textile fiber materials, especially of cellulosic fiber materials such as cotton or polyamide fibers such as nylon or wool. More particularly, in a first aspect, the present invention relates to fabric softening and brightening agents for household use in the softening and simultaneous brightening of cellulose, especially cotton fabrics.

Nowadays, a great many home laundry softeners contain optical brighteners. Addition of such brighteners increases the appeal of these products, which are usually supplied in the form of thick pastes to be dispensed from plastic pressure tubes and the like dispensers. These thick pastes are then diluted with water and form stable dilute aqueous dispersions which are highly suitable for home laundry. Use of these agents imparts a soft handle to the treated fabrics, and brightens them; moreover, depending on further adjuvants in these agents, additional advantages may be gained by treating fabrics with them, e.g. elimination of static electricity, easier drying and ironing, and others.

Brighteners are also included in softeners because detergent brighteners are partially "quenched" on the fabric by the brightener-free softeners. A 10-30% loss in brightness may thus be caused, depending on fluorescence level of the fabrics. Quenching is usually manifested as a dulling effect. However laundry washed with brightener-containing detergent is given a full, brilliant brightened aspect if rinsed with brightener-containing softener immediately after the washing.

Main ingredients of fabric softener compositions for household use are active quaternary compounds among which especially di-(hydrogenated tallow) dimethyl ammonium chloride and similar substances, or ethoxylated dialkyl dimethyl ammonium sulfate and equivalent compounds, or imidazolinium derivatives have been recommended.

Of the large number of known cationic, nonionic and anionic optical brighteners, only a handful of anionic brighteners have hitherto been found useful for incorporation into softener-brightener compositions.

Many of the known optical brighteners are not sufficiently soluble, some discolor the softener formulation and thus make the aspect of the latter unappealing, some cause separation or precipitations in the formulation, and

2

some are effective primarily on synthetic fibers, but not on natural fibers such as cotton.

The anionic brighteners which were found suitable for fabric softener application had to be highly soluble, compatible with the softener, and should not introduce free inorganic electrolyte into the formulation. A special advantage of anionic brighteners in softener formulations was seen to reside in formation of an ion complex with the cationic quaternary softener; solubility of the complex increases with solubility of the brightener. Free inorganic electrolyte was expected to lower solubility and, at high concentrations, even "salt out" the brightener.

The only brighteners hitherto recommended for use in softeners as satisfying the above requirements are anionic brighteners belonging to the class of bis-(triazinylamino)-stilbene-disulfonic acids.

Contrary to these requirements of the known brightener-softener mixtures, novel fabric softener-brightener compositions according to the first aspect of the present invention consist essentially of an aqueous dispersion of:

(a) A fabric softener falling under the formula

wherein

R represents alkyl of from 10 to 24 carbon atoms, each of R₁, R₂, R₃ represents alkyl of from 1 to 24 carbon atoms, and

X represents an anion, preferably the anion of a non-color-imparting acid, and preferably R₁ represents alkyl of 10 to 24 carbon atoms, the content of the softener in each liter of the composition amounting to at least about 20 grams, and preferably 50 to 100 grams.

(b) An oxacyanine optical brightener of the formula

where

Y represents hydrogen or lower alkyl, R', R'' each represent a lower alkyl group, R₃ and R₄ each represent a lower, unsubstituted or non-ionogenically substituted alkyl group,

X represents a colorless anion, and

n represents 0 or 1, the content of the brightener in the composition amounting per liter of the latter to about 0.3 to 15 grams, and preferably to 1 to 5 grams.

(c) Viscosity-adjusting additive, preferably electrolyte, such as weak organic acids, alkali metal or ammonium salts of the latter or similar electrolyte agents which influence the viscosity of thixotropic system; if viscosity coefficients above that of water are desired, e.g. for reasons of storage, depending on the nature of the container and the method of dispensing chosen, the amount of component (c) should be sufficient to impart to the entire composition a viscosity coefficient of at least about 2 centipoises. Viscosity coefficients in the range of 5 to 500 centipoises are preferred in composition for household use.

Furthermore, the compositions according to the invention may contain other smoothing agents, coloring agents, perfumes, emulsion stabilizers and antistatic agents; the balance of the composition consists of water.

Oxacyanine brighteners have been added in the past to quaternary salts of condensation products of formaldehyde with long chain fatty acid amides and the like sub-

stances useful as crease-proofing agents or water-proofing agents, in which solubility of the agents plays a secondary part or is even undesirable. Indeed, since the oxacyanine brighteners are poorly to very poorly soluble in water and practically insoluble in aromatic hydrocarbons, and, in the cold, in most other industrial solvents, they appeared to be very well suited for such known uses, while they were deemed unsuited for incorporation into fabric softeners.

As has been mentioned above, good solubility was deemed a paramount requirement for the latter.

The softener-brightener compositions according to the invention, however, are distinguished by an unexpected excellent dispersibility in water, in spite of the slight to very slight solubility of the brightener component. Moreover, while the known crease-proofing compositions containing oxacyanine brighteners are not stable in aqueous medium, but form precipitate of the brightener after a few hours of storage, the novel brightener-softener compositions according to the invention show, very surprisingly, an excellent stability, and can be stored for months without separation of its components.

Application of the softener-brightener compositions according to the invention for rinsing detergent-washed household laundry especially of cellulose fiber fabrics such as cotton, gives the goods a blueish white shade which is fast to light and gives the goods an improved soft handle.

The aforesaid blue fluorescence with, at the same time, good fastness to light is a further advantageous property, of the optical brightener-softener compositions according to the invention.

In Formula II defining the oxacyanine brightener component, R', R'', R₃ and R₄ represent, for example, the methyl, ethyl, propyl, isopropyl, n-butyl, sec.-butyl, isobutyl or tert.-butyl group. Non-ionogenically substituted alkyl groups in the position of R₃ and R₄ have, as substituents, for example, a cyano group or halogen; examples are the β -cyanoethyl or a halogen alkyl group such as the β -chloroethyl group.

The colorless anion X of the compounds of Formula II represents, for example, chloride, bromide or the equivalent of an inorganic or organic oxygen acid of hexavalent sulfur.

In particularly active compounds of Formula II which are valuable because of their pure white effects, R', R'', R₃, R₄ are each the methyl group and X is the equivalent of the anion of an inorganic or organic oxygen acid of hexavalent sulfur, in particular the equivalent of a sulfate ion, metho- or etho-sulfate ion, p-tolueno- or benzene-sulfonate ion.

In aqueous rinsing baths, the softener-brightener compositions are used in such concentration that the content of optical brightener of Formula II in the liquor is preferably about 0.003 to 0.25% calculated on the textile goods to be brightened and softened. The content of softener of Formula I is 0.1 to 10% calculated on the weight of the goods.

According to a second aspect of this invention, there are provided softener-brightener compositions similar to those described hereinbefore, but in which the softener component of the mixture is of the formula

wherein

R, R' and R'' have the same meanings as in the preceding formulas each of the "alkylene" bridges has from 2 to 3 carbon atoms, and

Y represents one of the groupings

wherein

n represents an integer ranging from 1 to 20, and is preferably 1 to 3.

All details given with regard to the softener-brightener compositions under the first aspect of this invention apply equally to the compositions according to this second and to the following third aspect of the invention.

When applied in such concentration in the rinsing liquor that an amount of 0.1 to 5 grams of softener is deposited on every 100 grams of fiber material, excellent softening and brightening effects are achieved with the softener-brightener mixture according to this aspect of the invention especially on natural polyamide fibers such as wool, but also on acid acrylic fibers of the type containing sulfo and preferably also carboxyl groups (Courteille and Orlon type acrylic fibers).

At the same time treatment with the softener-brightener compositions imparts to treated fabrics made from cellulosic fibers such as cotton, but also from various synthetic fibers such as polyamide, polyester or polyacrylonitrile fibers a very satisfactory antistatic finish without any undesirably quenching effect on the brightener component.

According to a third aspect of this invention, there are provided softener-brightener compositions similar to those described hereinbefore, but in which the softener component of the mixture is a colloidally dispersible 1,2-substituted imidazoline salt, preferred softeners of this class falling under the formula

wherein

X and R have the same meaning as in the preceding formulas,

R₅ represents hydrogen or alkyl of from 1 to 18 carbon atoms,

R₆ represents alkyl of from 1 to 18 carbon atoms, hydroxy lower alkyl, higher fatty acyl-amino-lower alkyl and higher fatty acyl-oxy-lower alkyl, and

each of R₇ and R₈ represents hydrogen or alkyl of from 1 to 6 carbon atoms,

"higher fatty acyl" representing the radical of a fatty acid of from about 9 to 19 carbon atoms.

"Lower" in connection with an aliphatic radical as used in this specification and the appended claims means that such radical has not more than 4 carbon atoms.

When textile fabrics and the like materials made from cellulosic fibers such as cotton or woolen materials or various synthetic fibers such as polyamide, polyester or polyacrylonitrile fibers are treated e.g. in the household wash or in a single bath process with a rinsing liquor to which a softener-brightener composition according to this aspect of the invention has been added, these materials are simultaneously given a softened handle and an antistatic finish without the brightening effect on the textile material being noticeably quenched thereby.

Treatment of the above-mentioned fiber materials with brightener-softener compositions according to the second and third aspect of the invention, preferably in the form of homogeneous, very stable aqueous dispersions, allows wool and/or cellulose fiber material such as cotton to be brightened and softened simultaneously with the finishing of other fibers, e.g. the treatment of synthetic fibers liable to accumulate static charges, with water soluble, cation-active agents acting as antistatics.

The content of the antistatic component in the treatment liquors should be sufficient to deposit on the fibers advantageously 0.5 to 50% calculated on weight of the textile material the handle of which is to be softened and/or which is to be rendered antistatic.

The high yield rates of both active components present in the compositions according to all three aspects of the invention, which are attained in the treatment of textile goods therewith, i.e. favorable ratio between amount of each component deposited on the fibers to the amount in the liquor containing the composition also distinguishes the latter from known fabric softener-brightener compositions.

The three aspects of the invention are further illustrated by the following non-limitative examples.

10 parts of wool flannel are treated for 10 minutes at a

temperature of 40° in 300 parts of aqueous liquor containing 0.7 part of a softener of the formula

Where not otherwise expressly stated, parts and percentages are given therein by weight. The temperatures are in degrees centigrade. The relationship of parts by weight to parts by volume is as that of grammes (g.) to milliliters (ml.)

Example 1

10 parts of cotton cretonne are introduced into 300 parts of an aqueous liquor having a temperature of 35° and containing 0.5 part of the softening-brightening agent, produced as described below, which liquor is an aqueous dispersion of di-(hydrogenated tallow)-dimethyl ammonium chloride and 3,3'-dimethyl-5,5'-dimethoxy-oxacyanine-p-toluene-sulfonate, and are lightly stirred therein for 10 minutes. Thereupon, the cotton cretonne is removed from the aqueous liquor and air-dried. The fabric then shows a beautiful white effect and, in addition, has a soft handle.

Production of the softener-brightener composition

86.7 g. of commercially available di-(hydrogenated tallow)-dimethyl ammonium chloride fabric softener consisting of a mixture of 35
18 parts of di-hexadecyl-dimethyl ammonium chloride, 56.25 parts of di-octadecyl-dimethyl ammonium chloride, 0.75 part of di-octadecenyl-dimethyl ammonium chloride, 18 parts of isopropanol.
6.5 parts of water and
0.5 part of sodium chloride

are heated with stirring at a temperature of 45-50°, 2.0 g. of 3,3'-dimethyl-5,5'-dimethoxy-oxacyanine-p-toluene-sulfonate are added and the whole is stirred for 30 minutes. The temperature is then raised to 55-60° and warm water is added to make up a total weight of 1000 g.

A stronger brightening effect is obtained when using 5.0 g. in lieu of 2.0 g. of the above brightener in the above composition.

Example 2

10 parts of cotton cretonne are treated for 15 minutes at a temperature of 40° in 300 parts of an aqueous liquor containing 0.6 part of bis-stearyl-bis-methyl ammonium chloride, and 0.01 part of the compound of the formula

The aforesaid agents, as well as those mentioned in the following examples are introduced into the liquor in the form of an aqueous mixed fabric softener-brightener composition produced in a similar manner as described in the preceding examples.

After drying, the treated fabric has a beautiful white effect and, in addition, has a soft handle.

A considerably stronger white shading is obtained if,

in the above example, 0.025 part of the brightening agent mentioned are used instead of 0.01 part.

When Example 1 is repeated, but the brightening agent used in the composition employed in that example is replaced by equimolar parts of one of the compounds listed in Table I infra, fabrics having a similar white effect and soft handle are attained.

Example 3

10 parts of wool flannel are treated for 10 minutes at a temperature of 40° in 300 parts of aqueous liquor containing 0.7 part of a softener of the formula

15 and 0.025 part of the brightening agent given in Example 1. The material so treated has a strong white effect in daylight and has, in addition, a soft handle.

Similar results are obtained by treating 10 parts of cotton fabric in lieu of wool flannel by the procedure of

Example 3.

The brightener in Example 3 can be replaced by equimolar parts of the brightening agents given in Table I; woolen or cotton fabrics are then obtained having similar white effects and soft handle. Better antistatic properties are also imparted to these materials by using 1.0 to 1.8 parts of the softener in lieu of 0.7 part.

The fabric softener used in Example 3 is produced as follows:

270 g. of stearyl alcohol are heated to melting, 104 g. of chloroacetic acid are added to the melt and the mixture is heated at 170-175° until no more water distils off. This is the case after about 90 minutes. The reactive mass is then subjected to fractional distillation and the fraction boiling at 175 to 205° at 0.5 torr is isolated. It consists of stearyl chloroacetate (yield rate about 93%).

100 g. of this ester are heated to 50-60°, 17 g. of pentamethyldiethylenetriamine are added, and the whole is heated to about 85° on the water bath. An exothermic reaction sets in which raises the temperature of the mixture to about 107°. After the reaction has abated, heating to about 90-95° is continued for 3 hours.

The mixture is stirred till, it becomes highly viscous at cooling and finally solidifies. 117 g. of the quaternary softener compound of the formula given in Example 4 are obtained.

80 g. of the pulverized softener compound are incorporated into the softener-brightener composition as described in Example 1 in lieu of the softener used in the latter composition.

Example 4

Similar results as in Example 3 are obtained when using an equivalent amount of the compound of the formula

70 is used instead of the softener used in Example 3, while following otherwise the same procedure as in that example.

The softener used in Example 4 is produced as follows: 560 g. of chloro sulfonic acid are added dropwise to 300 g. of triethylene glycol maintained by cooling at a temperature of 25-30°. After the dropwise addition is complete, the temperature is raised to 40-45° and the

viscous mixture is stirred at this temperature for one hour.

The mass is then passed through an inflow funnel having a wide outlet tube into solution cooled to 5-10° which is prepared from 68 g. of caustic soda, dissolved in 1140 g. of aqueous 30% sodium hydroxide solution and the whole is stirred for one hour at the same temperature of 5-10°. 709 g. of aqueous 40% dimethylamine solution is added to the resulting paste and the mixture is then heated for 12 hours in an autoclave at a temperature of 170-175°.

The contents of the autoclave are cooled to 40-45° and 300 g. of caustic soda are added in the cold to the reaction mixture. After the entire caustic soda has been dissolved the oily upper layer formed is separated off and a further 100 g. of caustic soda are added thereto while heating mildly. When this caustic soda is dissolved the aqueous bottom layer is drawn off. During the separation of the base with the aid of caustic soda, a strong current of air is blown through the reaction mass, and excess dimethylamino thus set free is recovered by introduction of the air stream loaded therewith into water.

10 g. of animal charcoal are added to the oily upper layer, the mixture is then filtered and freed from residue dimethylamine by applying a water jet vacuum at room temperature. 335 g. of 88.6% tetramethyl-triethylene-diamine (yield rate 72-73%) are thus obtained, 118 g. of tetramethyl-triethylene-diamine, are added to 346.5 g. of stearyl chloroacetate, at a temperature of 50-60°. The mixture is then heated on a water bath. At a temperature of about 75° an exothermic reaction sets in, whereby the temperature rises automatically to about 120°-125°, and the reaction mass becomes waxy. While cooling, it is stirred for as long as possible and is then left at a temperature of 90-95° for 3 hours. After cooling to room temperature the completely solidified reaction mass is ground; 464 g. of the quaternary compound used as softener in Example 4 is obtained.

Example 5

10 parts of cotton cretonne are treated for 15 minutes at a temperature of 40° in 300 parts of a liquor containing 0.3 part of 2-oleyl-1-alkyl-imidazoline acetate and 0.02 part of the brightening agent used in Example 1. The fabric so treated has a beautiful white effect, a soft handle and does not tend to accumulate static charges.

The brightening agent mentioned above can be replaced by equimolar parts of the compounds mentioned in Table I; similar white effects and a soft handle are then obtained, by following the same procedure as this example. ("Alkyl" in the above softener has from 15-17 carbon atoms.)

Example 6

Still softer handle and equally good, unquenched brightening effects are obtained when repeating Example 5, but using a softening composition containing per 1000 g. thereof 90 g. of 1-methyl-1-(β -stearylaminooethyl)-2-heptadecyl-imidazoline chloride and 3 g. of the brightening agent used in Example 1.

Example 7

10 parts of cotton cretonne are treated for 15 minutes at a temperature of 40° in 300 parts of a liquor containing 0.05 part of bis-stearyl-bis-methyl ammonium chloride, 0.3 part of 2-oleyl-1-methyl-imidazoline acetate and 0.02 part of the brightener used in Example 1. The fabric so treated has a strong white effect in daylight. In addition it has a soft handle.

The brightening agent given above can be replaced by equimolar parts of the brightening agents given in Table I; the fabric treated as described in the above Example 4 then have a similar white effect and soft handle.

Example 8

Similar results as in Example 5 are also obtained when using in that example an equivalent amount of 1-stearyl-

amino-ethyl-2-heptadecyl-imidazoline lactate as softener component.

Example 9

10 parts of cotton poplin which have been given an anti-crease processing consisting of 100 g. per liter of a reactive resin and 10 g. per liter of magnesium chloride, are treated at a temperature of 40° for 12 minutes in 300 parts of a liquor containing 0.04 part of bis-stearyl-bis-methyl-ammonium chloride and 0.01 part of the brightener given in Example 1. The fabric so treated has a beautiful white effect and, in addition, a soft handle. If, in the above example, 0.025 part of the brightening agent mentioned are used instead of 0.01 part, an equally soft handle and a considerably stronger white effect of the fabric is obtained.

The brightening agent mentioned above can be replaced by equimolar parts of the compounds given in Table I whereupon fabrics having a similar white effect and soft handle are obtained by following the procedure of Example 9.

Example 10

10 parts of cotton fabric are entered into 300 parts of a rinsing bath containing 0.6 part of bis-stearyl-bis-methyl ammonium chloride, and 0.001 part of the brightening agent given in Example 1, and the goods are slightly moved therein for 15 minutes at a temperature of about 40°. The cotton fabric is then removed from the rinsing bath and air-dried. The fabric has a beautiful brightening effect and a soft handle. When this cotton fabric is treated under the same conditions in other rinsing baths of the same composition, as is the practice in household washing, the white content of the fabric slowly increases and, with the concentrations given, a maximal brightening effect is attained after 16 consecutive rinsing baths. Determined on the Hunter scale for assessing whiteness, the white content increases as shown in the following table:

Times fabric was rinsed	Degree of whiteness
Once	113
Twice	117
Four	120
Eight	124
Sixteen	125

The effects obtained show a brilliant white shading. The amount of brightener mentioned in the above example can be changed within wide margins. Rinsing baths containing from 0.0003 to 0.027 part of brightener can be used. The number of rinsing baths necessary to attain the maximal brightening effect is then correspondingly altered.

When Example 9 is repeated, but the softener by that used in Example 3, or if 0.01 or 1.5 part of the agent employed in Example 9 are used instead of 0.6 part if the temperature of the rinsing bath is 20° or 50° and the time of the fabric in the baths is 1 minute or 30 minutes, similar brightening effects and soft handle are obtained.

When Example 9 is repeated but rinsing baths are used which further contain 0.3 to 1 part of 3-oleyl-1-alkyl-imidazoline acetate and, in addition to cotton, also synthetic fibers such as polyamide, polyester or polyacrylonitrile fibers are treated in these baths, then the synthetic fibers are given an antistatic finish without the white effects on the cotton described above being noticeably quenched.

When Example 9 is repeated but the brightening agent used therein is replaced by equivalent amounts of one of the brighteners given in Table I, fabrics having similar white effects and soft handle are then obtained.

Example 11

20 parts of yarn of fibers made from polyacrylonitrile having a polymerization degree of about 35,000 and about 154 millimols of carboxyl groups per 100 g. thereof, but 75 is free from sulfo group, yarn are given a pre-rinse at a

temperature of 60° in 600 parts of water containing 0.6 part of non-ionogenic washing agent nonylphenol poly-glycol ether having 8-15 ethyleneoxy groups, and 0.3 part of acetic acid and then the yarn is rinsed with water. The yarn is then introduced at 60° into an aqueous rinsing liquor containing 10 parts of a softening-brightening composition as described below, whereby 0.03 part of the compound of the formula

and 0.9 part of 1-methyl-1-(β -stearoylamino-ethyl)-2-heptadecyl-imidazoline chloride have been introduced thereinto. The liquor further contains 0.6 part of oxalic acid, 0.075 part of sodium metabisulphite and 0.15 part of a mixture of sodium tetrametaphosphate and sodium hexametaphosphate. The temperature of the liquor is raised within 20 minutes to 96-98° and kept for another 30 minutes at this temperature. The yarn is then washed first with lukewarm and then with cold water and dried.

The yarn thus treated has a very beautiful white effect in daylight.

Similar brightening and softening effects are obtained if the brightener mentioned in the above example is replaced by an about equal amount of one of the brighteners listed in Table I below and if the softener used in this example is replaced by the same amount of one of the softeners listed in Table II below, and otherwise the procedure given in Example 11 is followed.

Example 12

Similar brightening and softening effects are obtained by repeating Example 11, but treating 20 parts of fabric consisting of polyacrylonitrile fibers having a polymerization degree of about 35,000 and 46 millimol of sulfonic acid groups and 17 millimol of carboxylic groups per 100 g. fiber weight, and otherwise following the procedure.

TABLE I

The brighteners given in this table fall under the formula

in which R', R'', R₁, R₂ and X have the meanings given below:

No.	R'	R''	R ₁	R ₂	X
1	CH ₃	CH ₃	CH ₃	CH ₃	OSO ₂ -C ₆ H ₄ -CH ₃
2	CH ₃	CH ₃	CH ₃	CH ₃	OSO ₂ -C ₆ H ₄ -Cl
3	CH ₃	CH ₃	CH ₃	CH ₃	Cl
4	CH ₃	CH ₃	CH ₃	CH ₃	(SO ₃) ₂
5	CH ₃	CH ₃	CH ₃	CH ₃	O-SO ₂ -O-CH ₃
6	CH ₃	CH ₃	CH ₃	CH ₃	OSO ₂ -C ₆ H ₄ -CH ₃

7	CH ₃	CH ₃	CH ₃	CH ₃	OSO ₂ -C ₆ H ₄ -CH ₃
8	CH ₃	CH ₃	CH ₃	CH ₃	OSO ₂ -C ₆ H ₄
5	C ₂ H ₅	C ₂ H ₅	CH ₃	CH ₃	OSO ₂ -C ₆ H ₄ -CH ₃

or under the formula

25 wherein R', R'', R₁, R₂, Y' and X have the meanings given below

No.	R'	R''	R ₁	R ₂	Y'	X
10	CH ₃	CH ₃	CH ₃	CH ₃	H	OSO ₂ -C ₆ H ₄ -CH ₃
11	CH ₃	CH ₃	CH ₃	CH ₃	OSO ₂ -C ₆ H ₄ -CH ₃	

TABLE II

- 35
- (1) 1-oleyl-2-heptadecyl-imidazoline acetate,
  - (2) 1-octadecyl-2-heptadecyl-imidazoline chloride,
  - (3) 1-octadecyl-2-heptadecyl-imidazoline sulfate,
  - 40 (4) 1-(2-stearoylaminoethyl)-2-heptadecyl-imidazoline lactate,
  - (5) 1-(2-stearoylaminoethyl)-2-heptadecyl-imidazoline benzoate,
  - (6) 1-(2-stearoylaminoethyl)-2-pentadecyl-imidazoline chloride,
  - 45 (7) 1-(2-stearoylaminoethyl)-2-heptadecyl-imidazoline citrate,
  - (8) 1-(2-stearoylaminoethyl)-2-heptadecyl-imidazoline formate,
  - 50 (9) 1-(2-ethylstearate)-2-heptadecyl-imidazoline tartrate,
  - (10) 1-coconut oil fatty acyl-amino ethyl-2-heptadecyl-imidazoline acetate,
  - (11) 1-methyl-1-(β -stearoylamino-ethyl)-2-heptadecyl-imidazoline chloride,
  - 55 (12) 2-cetyl-1-(2¹-stearoyl-amidoethyl)-1-sulfopropyl-imidazolinium sulfobetaine.

65 9.8 g. of 2-methylmercapto-5-methoxybenzoxazole are dissolved in 36 g. of chlorobenzene while excluding moisture.

70 18.8 g. of methyl p-tolene sulfonate are added dropwise to the solution within one hour while keeping the mixture at 125-130°, and the whole is then stirred for one more hour under weak reflux. 8.2 g. of melted 2-methyl-5-methoxybenzoxazole are then added dropwise to the reaction mixture at 135-140° within 2 hours and, on completion of the addition, the whole is stirred for another two hours at this temperature. The reaction

Example 13

mixture is allowed to cool to room temperature, 17 g. of water are added and the pH is adjusted to about 5.5 by the addition of an aqueous solution of about 2.5 g. of sodium hydroxide. The crude reaction product is filtered off and washed, first with chlorobenzene and then with water. The crude product is purified by stirring it at reflux temperature for 15 minutes into a mixture of 22 g. of chlorobenzene and 16.5 g. of water the pH of which is about 5.5, cooling to 20° and adjusting the pH to 7.5 with dilute sodium hydroxide solution. The pale yellow product is filtered off, washed with chlorobenzene and water and then dried under vacuum at 100–110°. 3,3'-dimethyl-5,5'-dimethoxy-oxacyanine-p-toluene sulfonate is obtained as a yellowish powder which melts at 289–291° with decomposition (M.P. uncorrected). The product is an excellent agent for brightening cotton from rinsing baths in the presence of cation active compounds. It

are added to the mixture so that the temperature does not drop below 40–45°, and the pH is adjusted to and maintained at a weak alkaline reaction to mimosa paper by the addition of sodium hydroxide solution. At the aforesaid temperature of 40–45°, 30.6 g. of dimethyl sulfate are added dropwise within 30 minutes and the whole is stirred for another 2 hours at 50–55°. The mixture is then cooled to 20–25°, 33.5 g. of xylene are added, stirring is continued for one hour and, after the addition of 1.0 g. of Hyflo the reaction mixture is filtered. After separating the two phases in the filtrate, the upper xylene phase is dehydrated by azeotropic distillation, the xylene is distilled off under ambient pressure and the reaction product is fractionated in vacuo at 167–169°/13 torr. 2-methylmercapto-7-methoxybenzoxazole is obtained as a whitish crystal mass which melts at 55–57° (uncorrected).

Example 16

can also be used for the brightening of nylon and, in acid baths, for the brightening of polyacrylonitrile fibers.

Example 14

27.9 g. of 4-methoxy-2-amino-1-hydroxybenzene are added to a mixture of 7.5 g. of glacial acetic acid and 21.6 g. of acetic acid anhydride at a temperature of 80–85°. On completion of the addition, the whole is stirred for 6 hours at moderate reflux temperature whereupon first the acetic acid and the remaining acetic acid anhydride are distilled off under normal pressure and then the crude product is fractionated at 125–126°/13 torr. To remove traces of adherent acid, the crude product is dissolved in an emulsion of xylene and water and the pH is adjusted to 7 with sodium carbonate. After removal of the aqueous phase, the xylene phase is first azeotropically dehydrated and the product is then redistilled in vacuo. 2-methyl-5-methoxybenzoxazole is obtained as an almost white crystalline mass which melts at 39–40° (uncorrected).

25 9.8 g. of 2-methylmercapto-5-methoxybenzoxazole are reacted analogously to Example 13 with 18.8 g. of methyl p-toluene sulfonate in 36 g. of chlorobenzene and the reaction product is then further condensed with 8.1 g. of 2,5,6-trimethylbenzoxazole instead of with 8.2 g. of 2-methyl-5-methoxybenzoxazole. With otherwise the same procedure and the same method of purification, 3,3',4,5-tetramethyl-5'-methoxyoxacyanine-p-toluene sulfonate is obtained as a yellowish powder which melts at 248–250° with decomposition. (M.P. uncorrected). This product is an excellent agent for the brightening of cotton from rinsing baths in the presence of cation active compounds.

Example 17

This compound is produced analogously to Example 14 for the production of 2-methyl-5-methoxybenzoxazole except that 27.4 g. of 4,5-dimethyl-2-amino-1-hydroxybenzene are used instead of 27.9 g. of 4-methoxy-2-amino-1-hydroxybenzene. 2,5,6-trimethylbenzoxazole thus obtained boils at a temperature of 139–142°/15 torr, and solidifies to a white crystal mass.

Example 18

50 By using, in Example 13, 7.4 g. of 2-methylmercapto-5-methoxybenzoxazole instead of 9.8 g. of 2-methylmercapto-5-methoxybenzoxazole and otherwise following the same procedure as described in Example 13, condensation with 18.8 g. of methyl p-toluene sulfonate and 8.2 g. of 2-methyl-5-methoxybenzoxazole under otherwise the same conditions, affords 3,3',5-trimethyl-5-methoxy-oxacyanine-p-toluene sulfonate in the form of a yellowish powder which melts at 261–263° with decomposition. The compound is a good agent for the brightening of cotton from rinsing baths in the presence of cation active compounds.

Example 19

Example 15

A solution of 12.4 g. of potassium hydroxide in 30 g. of ethanol, having an initial temperature of 20° is added so slowly to a mixture of 20 g. of carbon disulfide and 20 g. of ethanol that the temperature never rises above 40°. On completion of the reaction, 27.9 g. of 4-methoxy-2-amino-1-hydroxybenzene are added within 30 minutes, the whole is heated from 40° to 76° within 4 hours and then kept for one hour under weak reflux at about 76°. 50 g. of about 50°-warm water are added to the reaction mixture in such a manner that the temperature of the mixture does not drop below 70°, and the excess of carbon disulfide and ethanol is then distilled off. When the distillation temperature has reached 95–97°, another 27 g. of water

This compound is produced analogously to 2-methylmercapto-5-methoxybenzoxazole by repeating Example 14, but using 24.6 g. of 4-methyl-2-amino-1-hydroxybenzene instead of 27.9 g. of 4-methoxy-2-amino-1-hydroxybenzene. 2-methylmercapto-5-methylbenzoxazole which is thereby obtained, boils at 149-151°/11 torr and solidifies to a white crystal mass which melts at 42-43° (uncorrected).

We claim:

1. A fabric softening and brightening composition consisting essentially of

- (a) an aqueous base,
- (b) a fabric softener falling under the formula

wherein

R is alkyl of from 10 to 24 carbon atoms, each of R₁, R₂, R₃ is alkyl of from 1 to 24 carbon atoms, and X is chloride ion, the content of the softener in each liter of the composition amounting to at least about 20 grams;

(c) an oxacyanine optical brightener of the formula

wherein

Y represents hydrogen or methyl group, R', R'', R₃ and R₄ are methyl or ethyl groups, X is chloride or bromide ions, the content of the brightener in the composition amounting per liter of the latter to about 0.3 to 8 grams.

2. A fabric-softening and brightening composition as described in claim 1, further comprising

(c) a weak organic acid viscosity-adjusting additive in an amount sufficient to impart to the entire composition a viscosity of at least about 2 centipoises.

3. A fabric-softening and brightening composition as described in claim 1, wherein the content of said fabric softener in each liter of the composition amounts to about 50 to 80 grams.

4. A fabric-softening and brightening composition as described in claim 1, wherein the content of said optical brightener in each liter of said composition amounts to about 1 to 3 grams.

5. A fabric-softening and brightening composition as described in claim 1, wherein said fabric softener is di(hydrogenated tallow) - dimethyl ammonium chloride.

6. A fabric-softening and brightening composition consisting essentially of

- (a) an aqueous base,
- (b) a fabric softener having the formula

5

wherein

R is alkyl of from 10 to 24 carbon atoms, each of R₁, R₂, R₃ is alkyl of from 1 to 24 carbon atoms, and X is chlorine, the content of the softener in each liter of the composition amounting to at least about 20 grams, and

(c) an oxacyanine optical brightener having the formula

wherein A represents an anionic equivalent selected from the group consisting of chloride, sulfate, monolower alkyl sulfate, phenylsulfonate and chlorophenyl-sulfonate.

7. A fabric-softening and brightening composition consisting essentially of

- (a) an aqueous base,
- (b) a fabric softener having the formula

wherein

R is alkyl of from 10 to 24 carbon atoms, each of R₁, R₂, R₃ is alkyl of from 1 to 24 atoms, and X is chlorine, the content of the softener in each liter of the composition amounting to at least about 20 grams; and

(c) an oxacyanine optical brightener having the formula

wherein A represents lower alkyl-phenyl-sulfonate.
